UNITED STATES PATENT OFFICE.

OTTO A. HENDERSEN, OF RACINE, WISCONSIN.

PRACTICE GOLF-BALL DEVICE.

Application filed April 25, 1928. Serial No. 272,698.

This invention relates to improvements in practice golf ball devices.

It is the primary object of the present invention to provide a practice device particularly useful out-of-doors for golfers in perfecting their game.

A further object of the invention is to provide in a practice golf ball device, an anchoring member, a ball, and an elongated yieldable connection or tether between the ball and the anchor, arranged so that the ball may be struck as in actual play and be limited in its flight by the yieldable connection.

A further object of the invention is to provide a device of the class described which is readily portable and which may be set up very easily and quickly.

A further object of the invention is to provide a device of the class described which defines the flight of the ball and limits the projection of the same, enabling the player to determine the correctness and accuracy of the hit.

A further object of the invention is to provide a practice golf ball device of the class described which is especially safe in its use in that the danger of breakage is minimized and in which any of the constituent parts are susceptible of ready replacement.

A further object of the invention is to provide a practice golf ball device which is of very simple construction, is strong and durable, is inexpensive to manufacture, is efficient in its operation, and is well adapted for the purposes described.

With the above and other objects in view, the invention consists of the improved practice golf ball device and its parts and combinations as set forth in the claims, and all equivalents thereof.

In the accompanying drawing in which the same reference characters indicate the same parts in all of the views:

Fig. 1 is a view showing the device in position for use;

Fig. 2 is an enlarged fragmentary detail sectional view showing a portion of the anchoring member and the inner end portions of the parts making up the yieldable connection or tether;

Fig. 3 is an enlarged sectional view of the ball showing the manner in which the outer end portion of the tether is connected thereto; and

Fig. 4 is a sectional view taken on line 4—4 of Fig. 2.

Referring now more particularly to the drawing, it will appear that the numeral 5 indicates an anchoring member having an elongated screw-threaded shank 6 with a head portion 7 which is externally threaded, as at 8, and having therein, below the threaded portion, a transverse bore 9, through which may be removably extended an elongated operating rod or handle 10. In practice, the handle is grasped and the shank portion 6 is screwed into the ground to about the depth shown in Fig. 1, leaving exposed the head portion 7.

Adapted to be removably threaded onto the head portion is a tubular socket or cap member 11. The lower portion of the bore of said member 11 is enlarged and threaded, as at 12, and an annular internal shoulder 13 is formed.

An annular connecting clip 14, shaped as shown in Fig. 4, is mounted on the top of the head portion 7, and the lower looped end portion 15 of an elongated inner spring member 16 is detachably connected to the mid-portion of said connecting clip. The lower flared portion of an intermediate spring member 17 is mounted on the outer portion of said clip and mounted on the flared portion of the member 17 is the lower flared end portion of an outer spring member 18. As shown in Fig. 2, said last mentioned flared end portions lodge under the annular shoulder 13 of the cap member and in this way the flared end portions of the spring members 17 and 18, as well as the connecting clip 14 are removably clamped between said shoulder 13 of the cap member and the top of head portion 7. Obviously, if the anchor member be unscrewed from the cap member, said spring members may be withdrawn through the cap member.

Both end portions of the elongated inner spring member are wound back forming double thicknesses for strength, as indicated at 16' and 16''. As shown in Fig. 1, the re-wound portion 16' is of a considerable length, being greater than the entire length of the intermediate spring member 17. The entire length of the spring member 16 is approximately five times that of the intermediate spring member 17, and the latter is about twice the length of the outer spring member 18 and all of said spring members are of graduated gauges of tempered wire. All three of said spring members, connected as shown, form a yielding, elongated connecting member or tether, and the reinforce-

ment provided by the members 17 and 18 is adjacent the anchoring member where the strain or bending is the greatest.

The outer end portion of the elongated 5 spring member 16 carries a short chain 19. A heavy staple 20, shaped as shown in Fig. 3, and having pronged arms, has the latter driven into a golf ball 21 of standard construction, and the other end portion of the 10 chain 19 is connected with the intermediate projecting portion of said staple.

In use, the anchoring member may be easily and securely extended into the ground with little exertion, and the ball is positioned 15 at a distance therefrom, wherever convenient. The ball is struck in the usual manner, and takes a limited course, being restrained by the yieldable tether which absorbs the shocks. The manner in which the ball carries, and its course, will indicate the correctness of the hit.

From the foregoing description, it will be seen that the improved practice golf ball device is of simple and novel construction, and 25 is well adapted for the purposes set forth.

What is claimed as the invention is:

1. A practice golf ball device, comprising a golf ball, a ground penetrating anchoring member and an elongated tether between said ball and said anchoring member and detachably connected to the latter, said tether being of a retractile spring throughout its entire length.
2. A practice golf ball device, comprising a golf ball, an anchoring member having a screw-threaded shank portion and a removable cap, and an elongated spring tether between the ball and said anchoring member and detachably engaged by said cap.
3. A practice golf ball device, comprising a golf ball, an anchoring member, a spring tether secured at its outer end portion to the ball and at its inner end portion to the anchoring member, and a yieldable reinforcing member surrounding the inner end portion of the tether.
4. A practice golf ball device, comprising a golf ball, an anchoring member, a spring tether secured at its outer end portion to the ball and at its inner end portion to the anchoring member, and a yieldable reinforcing

member surrounding the inner end portion of the tether, the inner end portion of said tether and said reinforcing member being detachably secured to said anchoring member. 55

5. A practice golf ball device, comprising a golf ball, an anchoring member, a spring tether between said ball and said anchoring member, a yieldable reinforcing member surrounding a portion of the tether adjacent 60 said anchoring member, and a removable cap detachably clamping the tether and the reinforcing member to said anchoring member.

6. A practice golf ball device, comprising a golf ball, an anchoring member, a spring tether secured at its outer end portion to the ball and at its inner end portion to the anchoring member, and a plurality of yieldable reinforcing members surrounding the 65 inner end portion of the tether.

7. A practice golf ball device, comprising a golf ball, an anchoring member, a spring tether secured at its outer end portion to the ball and at its inner end portion to the anchoring member, and a plurality of yieldable reinforcing members surrounding the inner end portion of the tether, said reinforcing members and said tether being graduated as to thickness and length.

8. A practice golf ball device, comprising a golf ball, a barbed staple having its shanks extended into said ball, an elongated spring tether secured at its outer end portion to the medial portion of said staple, and an anchoring member secured to the inner end 85 portion of said tether.

9. A practice golf ball device, comprising an anchoring member having a shank portion and a head, a tubular cap member removably mounted on said head, an elongated tether member, an intermediate yieldable reinforcing member surrounding the inner end portion of said tether, an outer yieldable reinforcing member of less length than said intermediate member and surrounding a portion of the same, the inner end portions of the tether and both reinforcing members being clamped between said head and said cap member, and a golf ball secured to the outer end portion of said tether member.

In testimony whereof, I affix my signature.

OTTO A. HENDERSEN.
